UNITED STATES PATENT OFFICE.

ANKER PETERSEN, OF WINTHROP, MASSACHUSETTS, ASSIGNOR TO BOSTON MACHINERY COMPANY, OF BOSTON, MASSACHUSETTS, A CORPORATION OF MASSACHUSETTS.

BRAIDING-MACHINE.

1,105,452.

Specification of Letters Patent. Patented July 28, 1914.

Application filed February 29, 1912. Serial No. 680,574.

To all whom it may concern:

Be it known that I, ANKER PETERSEN, a subject of the King of Denmark, residing at Winthrop, in the county of Suffolk and State of Massachusetts, have invented new and useful Improvements in Braiding-Machines, of which the following is a specification.

This invention relates to improvements in braiding machines and particularly to the rotary type of braiding machine.

The object of this invention is to provide a braiding machine having a series of strand guides adapted to be revolved about a center upon a single support and a series of thread-mass carriers adapted to be revolved about said center upon a second support, said first and second supports being rotated simultaneously in opposite directions by a single rotat- ing means, thus producing a machine which may be operated at a very high rate of speed and which shall eliminate the friction and wear usually associated with a braiding machine having thread-mass carriers adapted to be independently revolved about a center by individual driving means or otherwise.

Another object of the invention is to provide supports for said thread-mass carriers upon the rotatable member by which said thread-mass carriers are revolved, said supports adapted to be rotated at a speed equal to the relative movement between said first and second mentioned supports, whereby the strands which are carried by said strand guides may be guided and fed beneath said thread-mass carriers, when in their lower-most positions, without injury thereto and without danger of causing slack thread being formed between said strand guides and the point on said machine at which the fabric is being constructed.

The invention consists in the combination and arrangement of parts whereby the above objects and other objects hereinafter appearing may be attained, as set forth in the following specification and particularly pointed out in the claims.

Referring to the drawings: Figure 1 is a section, part elevation, of a rotary braiding machine embodying my invention, with but two sets of thread-mass carriers and strand guides shown therein. Fig. 2 is a detail plan view of a portion of the machine shown in Fig. 1 with parts broken away and shown in section to more clearly illustrate the invention. Fig. 3 is a detail section, part eleva-

tion, taken on line 3—3 of Fig. 1. Fig. 4 is a detail section, part elevation, taken on the irregular line 4—4 of Fig. 1. Fig. 5 is a detail of one of the strand guide levers and the bracket upon which it is mounted.

Like numerals refer to like parts throughout the several views of the drawings.

In the drawings 8 is the frame of the machine provided with suitable supports 9, said frame is preferably spider shaped and has a central hub 10 adapted to support a central supporting tube 11, which is sur- mounted by a bushing 12 upon which the tubular fabric constructed by said machine is formed, and through which said fabric is guided into said central supporting tube 11 and downwardly to the idler 13 mounted upon said central hub and from which said fabric is drawn to the take-up mechanism not shown in the drawings. A sleeve 14 is rotatably mounted upon said central sup- porting tube and has secured thereon a beveled gear 15 adapted to rotate upon the upper face of the hub 10. A driving shaft 16 is journaled to rotate in a bearing 17 formed in the bracket 18 secured to a ring 19 which forms part of the frame 8, said shaft 16 has secured upon its outer end a driving pulley 20 and at its inner end a pinion 21 which engages the beveled gear 15. Upon the sleeve 14, above said gear 15, is a rotatable strand guide support 22 rotatably mounted on said sleeve and provided with gear teeth 23 adapted to engage said pinion 21 upon the opposite side of said pinion relatively to its engagement with the gear 15, whereupon when said pinion is rotated, said gear 15 and strand guide support 22 are rotated simultaneously in opposite direc- tions and at a uniform speed.

The strand guide support 22 is provided with a cylindrical rim 24 forming a sup- port for a series of thread-masses 25, said rim being provided with vertical slots 26 through which the stands 27, leading from said thread-masses 25, are adapted to ex- tend to the bushing 12 where the tubular fabric is being formed. Located outside of the slots 26 are strand guides 28, Fig. 5, through which said strands 27 are drawn and which are adapted to move said strands upwardly and downwardly within said slots, said strand guides being mounted upon levers 29 pivotally mounted upon brackets 30 secured upon a flange 31 ex-

tending laterally from said support 22, Figs. 1 and 2. A vibratory movement is imparted to said strand guides 28 and levers 29 by a cam roll 32 mounted on said levers and 5 engaging a groove 33, which may be varied according to the character of the work to be formed upon the machine, and formed in the stationary cam 34, said cam being secured to uprights 35 formed on the frame of 10 said machine. The strands 27 in their passage from the thread-mass 25 to the bushing 12 extend through the eye 30', which is located at the pivotal point of the lever 29, thence along said lever through the guides 15 36 and 37 to the guides 28 located at the end of said lever from which point, as hereinbefore described, they extend through the slots 26 to said bushing 12.

Fastened to the upper end of the sleeve 20 14 is a thread-mass carrier support 38 which is adapted to be rotated with said sleeve and in the opposite direction to that of the strand guide support 22, but at an equal rate of speed. A series of thread-mass carriers 25 39 are mounted upon said thread-mass carrier support and revolved about the axis of said tube 11, each being provided with a thread-mass 40 having a thread 41 leading therefrom through a guide 41' to the bushing 12. In the passage of the thread-mass carriers 39 about said center and relatively to said strand guides 28, the strands 27 are moved from a position above to a position below said thread-mass carriers and must 35 therefore pass beneath said thread-mass carriers when in their lowermost positions. To facilitate the passage of said thread beneath said carriers, I have provided means for feeding the same therebeneath, which consist of a series of radially disposed rotatable members 42, 42 arranged in pairs and each pair adapted to support a carrier, each of said members preferably consisting of a shaft 43 having rolls 44 and 45 located adjacent the inner and outer ends respectively of said shaft 43 and a pinion 46 secured adjacent to said inner roll 44. The rotatable members 42 are journaled at their opposite ends to rotate in bearings formed in the support 38, said members being preferably located in pairs within segmental apertures 47 which are formed by the radially disposed arms 48 and the annular rim 49 connecting the outer ends of said arms and the annular 55 rim 50, connecting the inner ends of said arms 48 and mounted upon a disk 51 secured on said sleeve 14. The outer bearings for said rotatable members 42, hereinbefore mentioned, are formed in the rim 49, while said 60 inner bearings are formed in brackets 51' secured upon the rim 50.

It will be noted that the rolls 45, located upon the outer ends of the rotatable members 42, are of a greater diameter than the 65 rolls 44 located adjacent to the inner ends

of said members. This difference is made in order that said outer roll may have a greater surface speed than said inner roll so that the strand 27 may be properly fed thereacross at a speed proportionate with the distance 70 thereof from the center about which said strand guides are revolved. The rotation of said members 42 is accomplished by means of a stationary beveled gear 52 formed in the shape of a disk and which is secured to said 75 center supporting tube, thereby preventing rotation thereof, and has, upon its outer lower margin a series of gear teeth 53 which engage the pinions 46, whereupon said members are rotated by the relative movement 80 of the support 38 and said gear 52. The gear 52 is slightly cone-shaped and the rolls 44 and 45 are so placed that the uppermost points in their peripheries are substantially 85 in alinement with that portion of the outer face of said gear 52 which lies between said rolls and the center of said gear and provides a support for the strands adapted to guide the same in a substantially straight line from said guide 28 to said bushing 12, 90 at a time when said strand guide is in its lowermost position, and preventing said strands from becoming entangled in the projecting parts of said thread-mass carrier support. Each of the thread-mass carriers 95 39 preferably embodies in its construction a rectangular frame 54 adapted to rotatably support, at its inner end, a roller 55 and at its outer end a roller 56, said roller 55 being adapted to engage the adjacent rolls 44, 44 100 on the pair of rotatable members located in one of said segmental apertures, and the roller 56 is adapted to engage the adjacent rollers 45 upon the outer ends of said rotatable members. It will be seen that said carriers simply rest by their own weight upon the rolls 44 and 45 and in order that they may be retained in such relation during the operation of said machine, I have provided means adapted to engage a flange 57 105 110 formed upon and extending downwardly from the cylindrical portion of the support 22, said means preferably consisting of a pair of rollers 58, 58 rotatably mounted upon the outer end of each of said carriers and with their centers located above said rollers 56 and upon opposite sides of a vertical plane containing the axes of both of said rollers 55 and 56. The placing of said rollers 58, 58 upon opposite sides of said plane 115 is for the purpose of preventing said carrier from tipping sidewise or in other words to maintain the equilibrium of said carrier while it is being revolved about the center of said carrier support. The flange 57 is also provided in its under face with an annular groove 59 into which said rollers 58 120 are adapted to project and thereby said carriers are prevented from moving radially upon their respective supports thus prevent- 125 130

ing said rollers 56 and 55 from becoming disengaged from the rolls 45 and 44 respectively.

The operation of the machine is as follows: The thread-mass 40 is placed upon the spindle of the thread-mass carrier 39 and the thread drawn therefrom around the thread-mass carrier frame 54, through the guide 41 and thence to the bushing 12 at the center of said machine where it is connected with the threads leading from said series of thread-masses. The thread-mass carriers 39 are placed upon their respective pairs of rotatable members with the rollers 55 and 56 engaging the rollers 44 and 45 respectively, and with the rollers 58 engaging the groove 59 in the flange 57, the strands are then drawn from the thread-masses 25 through the thread guides in their respective levers to the thread guides 28, thence through the slots 26 and to the center bushing 12. Upon the rotation of the shaft 16 through the power transmitting instrumentalities, the pinion 21 is rotated which in turn rotates the gear 15 in one direction, and the gear formed by the teeth 23 upon the support 22, simultaneously in opposite directions. The gear 15 through the sleeve 14 imparts a rotatory motion to the thread-mass support 38 in the opposite direction to the strand carrier 22 and by said rotation the shafts 42 will be rotated through their respective pinions 46 engaging the gear 52. During the rotation of the support 22 the levers 29 are oscillated upon the brackets 30 by the roll 32 engaging the cam groove 33 which actuate the strand guides 28 whereby said strands 27 are moved above and below the thread-masses 40 and while said strands 27 are below said thread-masses 40 they will be fed beneath the same by the rotatory movement of said rods 44 and 45 in engagement with rolls 55 and 56 respectively.

The foregoing detailed description has been given for the purpose of elucidating the invention in its preferred embodiment and no undue limitations should be understood therefrom, but the claims should be construed as broadly as permissible in view of the prior art.

Having thus described my invention what I claim and desire by Letters Patent to secure is:

1. A braiding machine having, in combination, a carrier support, a plurality of pairs of rotatable members mounted on said carrier support, a series of thread-mass carriers each having rollers thereon adapted to engage one of said pairs of rotatable members, a strand guide support, a series of strand guides mounted on said support, mechanism adapted to create a relative rotary motion between said supports, means to actuate said strand guides to move strands over and under said thread-mass carriers, a flange ex-

tending downwardly from said strand guide support provided with an annular groove in the under face thereof and rollers arranged on said thread-mass carriers out of the path of the strands carried by said strand guides 70 adapted to project into said groove, to maintain the equilibrium of said carriers and prevent the same from becoming disengaged from their respective pair of rotatable supports. 75

2. A braiding machine having, in combination a strand guide support, a series of strand guides mounted thereon, having strands leading therefrom to a center, a thread-mass carrier support having a series 80 of segmental apertures, a pair of rotatable shafts radially disposed within each of said apertures and journaled at opposite ends thereof, rolls secured to opposite ends of said shafts respectively, a pinion secured upon each of said shafts respectively, a bevel gear adapted to engage said pinions, mechanism adapted to rotate said thread-mass carrier support relatively to said strand carrier support and said bevel gear, a series of thread-mass carriers carried by said rotatable shafts, rollers mounted at opposite ends of said carriers adapted to rotatably engage the rolls on said pairs of shafts respectively, means adapted to retain said carrier rollers 85 and said rolls in their rotatable engagement, and mechanism adapted to actuate said strand guides to move strands over and under said thread-mass carriers. 90

3. A braiding machine having, in combination, a strand guide support, a series of strand guides mounted thereon having strands leading therefrom to a center, a flange on said support, a thread-mass carrier support, a plurality of pairs of rotatable members mounted on said support, rolls located adjacent to each of the ends of said rotatable members, a series of thread-mass carriers, a roller at each end of said thread-mass carriers, having rolling engagement with the rolls on the adjacent ends of said pairs of rotatable members respectively, a pair of rollers mounted upon said thread-mass carriers, the centers of the rollers constituting said pair being located above the centers of said first named rollers and upon opposite sides of a vertical plane containing the axes of both of said first mentioned rollers and adapted to engage said flange 100 to retain said rolls and said first mentioned 105 rollers in rotatable engagement. 110

4. A braiding machine having, in combination, a strand guide support, a series of strand guides mounted thereon having strands leading therefrom to a center, a flange on said support provided with a groove, a thread-mass carrier support, a plurality of pairs of rotatable members mounted on said support, rolls located adjacent to each of the ends of said rotatable members, 120 125 130

a series of thread-mass carriers, a roller located at each end of said thread-mass carriers, having rolling engagement with the rolls on the adjacent ends of said pairs of 5 rotatable members respectively, a second pair of rollers mounted upon said thread-mass carriers, their centers located above the centers of said first named rollers and upon opposite sides of a vertical plane containing the axes of both of said first mentioned rollers and adapted to engage said groove to retain said rolls and said first mentioned rollers in rotatable engagement.

5. A braiding machine having, in combination, a stationary central supporting tube, a sleeve rotatable on said tube having a bevel gear secured thereto, a series of strand guides, a strand guide support rotatably mounted on said sleeve and provided with a 10 bevel gear, a bevel pinion adapted to engage said first and second mentioned bevel gears, and to impart a rotary motion thereto in opposite directions, a thread-mass carrier support secured upon said sleeve and provided with a series of rotatable members, pinions secured on said rotatable members respectively, a series of thread-mass carriers having rollers thereon adapted to engage said rotatable members, mechanism 15 adapted to actuate said strand guides to move strands over and under said carrier, a bevel gear secured to said stationary tube having teeth adapted to engage said pinions whereby said rotatable

members may be rotated by the rotation of 35 said carrier support to feed said strands between the contacting faces of said rollers and said rotatable members.

6. A braiding machine having, in combination, a rotary carrier support, a series of 40 radially disposed members rotatably mounted on said support, rolls located adjacent to the ends of said rotatable members, pinions secured upon the inner ends of said rotatable members, a stationary disk having 45 teeth upon its under margin, adapted to engage said pinions, the uppermost points in the peripheries of said rolls being substantially in alinement with that portion of the uppermost face of said disk lying between 50 said rolls and the center of said disk, a series of thread-mass carriers having rollers at opposite ends thereof, each of said rollers adapted to rotatably engage two of the adjacent rolls on said rotatable members, mechanism adapted to rotate said support relatively to said disk, a series of strand guides adapted to be rotated relatively to said thread-mass carriers, and means to actuate said guides to move strands over and 55 under said carrier.

In testimony whereof I have hereunto set my hand in presence of two subscribing witnesses.

ANKER PETERSEN.
